UNITED STATES PATENT OFFICE.

ATTILIO DI TOMASSO, OF EAST BOSTON, MASSACHUSETTS.

TAPE HOLDER.

Application filed November 22, 1923. Serial No. 676,277.

To all whom it may concern:

Be it known that I, ATTILIO DI TOMASSO, a subject of the King of Italy, and resident of East Boston, in the county of Suffolk and State of Massachusetts, have invented new and useful Improvements in Tape Holders, of which the following is a specification.

This invention relates to a holder for measuring tapes, chalk lines and the like, its object being to provide a convenient device for temporarily holding one end of a tape or line in fixed position while measurements or markings are being made.

A typical example of the invention is disclosed in the accompanying drawings in which:—

Fig. 1 is a plan view of the device showing the end of a tape indicated in broken lines attached thereto;

Fig. 2 is a side elevation of the device showing it in position for measuring, the article being measured being shown in section;

Fig. 3 is an end elevation of the device, and

Fig. 4 is a side elevation showing the device in another position of use with a chalk line attached thereto, the article being measured being shown in section.

Referring to the drawings the numeral 1 indicates the substantially flat body portion of the device which may be formed from sheet material if desired although preferably consisting of a casting or forging. The body portion has upstanding flanges 2 and 3 along its margins. These flanges are slightly convergent and are provided with channels 4 and 5 respectively in their opposed faces. These channels are adapted to engage and grip a tapering ring 7 such as is commonly furnished upon the end of a measuring tape. A pin 8 projects upwardly from the body portion and provides additional retaining means for the ring.

A lug 9 projects from the under side of the body portion and has a toothed surface 10 adapted to engage the end 11 of a board, metal bar or other element being measured. The toothed surface 10 is disposed in a plane substantially perpendicular to the upper surface of the body portion, said plane being also substantially tangent to that element 7^a of such ring most remote from the point of attachment of the ring to the tape. This element 7^a is that which commonly constitutes the zero point of the tape and with the

parts thus arranged said element lies flush with the surface 11 of the article to be measured. The pin 8 is so disposed that when engaging the inner surface of the ring the latter again occupies the position relative to the surface 10 just described.

A spur 12 projects laterally from the edge of the body portion and this spur is provided with a substantially flat surface 12^a which also lies in the plane of the surface 10. This spur may be driven into the article to be measured and may thus be used alternatively with the lug 9 for retaining the holder in desired position.

Usually measuring tapes are provided with rings 7 tapered slightly from their outer free extremities toward their point of attachment to the tape and when such a ring is employed it may be inserted between the channeled flanges 2 and 3 which by reason of their convergence grip the ring securely for holding it in position. When the ring is of other form the pin 8 forms a convenient means for retaining it in engagement with the holder.

Along the outer edge of flange 3 is provided a channel 14 and in the face of the body portion 1 there is an aperture 15. If a line or cord 16 is to be used, such as a "chalk line," one end may be passed up through aperture 15 and the main part of the line brought up around the body portion 1 and looped over flange 3, see Fig. 4. This loop will fit into channels 5 and 14 and upon being put under tension, will be securely retained therein. If now the spur 12 is driven into a board 11 or the like, the outer channel 14 will hold the cord firmly against the face of the board, and assist in retaining it against any possible tendency to slip while in use.

I claim:

1. A device of the class described comprising a body portion, a retaining lug depending from the lower side thereof, and a pair of oppositely disposed converging elements projecting above the plane of the upper surface of the body portion and constructed and arranged removably to grip the end ring of a measuring tape between them.

2. A tape holder comprising a body portion having a substantially flat upper surface, and spaced flanges projecting upwardly from said surface, said flanges converging toward each other and having chan-

nels in their opposed faces constructed and arranged removably to engage and grip the terminal ring of a measuring tape between them, and attaching means carried by the body portion.

3. A tape holder attachment comprising a body portion provided with a flange having channels in opposite sides thereof con-

structed and arranged to receive a chalk line or the like, said body portion having an aperture to retain the end of said line, and an attaching spur projecting from said body portion.

Signed by me at Boston, Massachusetts, this 17th day of November 1923.

ATTILIO DI TOMASSO.
